UNITED STATES PATENT OFFICE.

LEOPOLD SCHONWALD, OF NEW YORK, N. Y.

LOCK PROTECTOR.

1,408,477.

Specification of Letters Patent.

Patented Mar. 7, 1922.

Application filed September 9, 1920. Serial No. 409,170.

To all whom it may concern:

Be it known that I, LEOPOLD SCHONWALD, a citizen of the United States, residing at the borough of Manhattan, in the county of New York, city and State of New York, have invented certain new and useful Improvements in Lock Protectors, of which the following is a specification.

The improvements relate to locks, and particularly to locks of the cylinder type, and their objects are, among others, to protect such locks against being broken or opened otherwise than by a proper key.

Locks of this character are commonly composed of a barrel or cylinder enclosing tumblers and having a cap or head integral with the cylinder at the outer face of the door and provided with a suitable keyhole. This construction exposes the lock in such a manner that it may be broken by the use of a pipe wrench or other tool, the intruder using the tool to engage the cap or head of the cylinder and drawing it out and twisting it in such a manner as to break the connection which prevents rotation of the lock and thus turning the lock and opening the door. The present improvements provide simple and effective means for preventing this.

The improvements are illustrated in the accompanying drawings, in which Figure 1 is a vertical medial section of a lock protecting device with the parts of the lock enclosed therein indicated in full lines; Figure 2 is a view of the front or face of the lock with the protection; Figure 3 is a detail of the protecting cup in vertical medial section and an inside view thereof; Figure 4 shows similar views of the inside barrel and its flanges which are secured to the inside of the door; Figure 5 is an inside view and vertical section of the plate for securing the key disk, and Figure 6 is an edge and front view of the keyhole protecting disk.

The door is represented in vertical cross-section at 1 (Fig. 1), and the cylinder containing the tumblers at 2. 3 is the lock spindle extending to engage bolt-operating mechanism on the inner side of the door, and 4 is the face plate or cap of the cylinder preferably made integral with the cylinder, access to the tumblers being provided through the removable plate 5 at the back of the cylinder.

The barrel or sleeve 6 is secured to the inner face of the door by means of the

flanges 7 receiving suitable screws or other fastenings 8, which enter the material of the door, and in this sleeve the cylinder or casing 2 fits snugly, the bore of the part 6 being shaped to correspond with the shape of the said casing (see Fig. 4), so that it cannot be turned therein. The part 6 is exteriorly threaded, and receives the protecting cup 9, which is threaded interiorly, these two parts being adjustable lengthwise to accommodate different thicknesses of doors. When they have been adjusted to the thickness of the door a set screw 15 is passed through the opening in the part 9, and an opening in the part 6 made to align therewith and caused to press against the part 2 so as to hold all three parts securely in position. These set screws may be located on opposite sides, as shown.

The end 9' of the protecting cup or cap 9 is integral therewith, and this cap is made of hardened steel so that it cannot be broken by tools, and as it encloses the head and cylinder of the lock it will protect it securely.

In order to give access to the keyhole of the lock the end plate 9' is provided with an opening 10 which permits the key to be inserted therethrough and rotated. In the preferred form however a rotating disk 11 is mounted in this opening and is provided with a key slot 12 through which the key may be inserted. The disk 11 is rotatably mounted in the opening by means of its annular rib or flange 13 which is confined between the back of the end plate 9' adjacent to the opening and the grooved or stepped edge 14' of the plate 14, the said plate being provided with an opening corresponding with the opening 10. It is secured to the inner side of the end plate 9' by means of screws or other fastenings passed through its openings 14'', which are in alignment with the openings 9''' of the said end plate. If desired, however, the disk 11 and inside plate 14 may be omitted and the cap of the cylinder placed against the inside of the plate 9' with the keyhole opposite the opening 10.

In order to make clear the objects and advantages of the improvements it should be explained that it is a comparatively easy matter for one who wishes to break a lock of this character to engage the face or cap of the cylinder 4 with a pair of heavy pliers, cutting away sufficient wood or other material of the door to give access thereto, and

then to draw the cylinder out of the sleeve or barrel 6, and to then break the threaded lugs 16 or the screws 17, by which the cylinder is secured to the inner face of the door 5 by applying a pipe wrench or similar device to the cylinder and turning it. With the protecting device of the present improvements, however, this cannot be done since the parts of the lock are completely enclosed 10 in the casing composed of the cap 9 and the barrel 6, united by their engaging threads and by the set screws and secured to the inner side of the door by means of the flange 7.

What I claim is:

15 1. The combination with a cylinder lock comprising a lock spindle, a key and suitable tumblers, and a casing surrounding said tumblers and spindle adapted to be mounted in a door, of a protecting casing 20 comprising a sleeve member surrounding the said casing adapted to be secured to the inner side of a door and extending into the door and a cap having its outer end at the outer side of the door, extending inwardly 25 therefrom and overlapping and secured to the sleeve member in the interior of the door, said cap substantially closing the protecting casing.

2. The combination with a cylinder lock 30 comprising a lock spindle, a key and suitable tumblers, and a casing surrounding said tumblers and spindle adapted to be mounted in a door, of a protecting casing comprising a sleeve member surrounding 35 the said casing adapted to be secured to the inner side of a door and extending into the door and a cap having its outer end at the outer side of the door, extending inwardly 40 therefrom and overlapping and secured to the sleeve member in the interior of the door, said cap substantially closing the protecting casing and having an opening in its outer part to permit the insertion of the key.

45 3. The combination with a cylinder lock comprising a lock spindle, a key and suitable tumblers, and a casing surrounding said tumblers and spindle adapted to be mounted in a door, of a protecting casing comprising 50 a sleeve member surrounding the said casing adapted to be secured to the inner side of

a door and extending into the door and a cap having its outer end at the outer side of the door, extending inwardly therefrom and overlapping and secured to the sleeve member in the interior of the door, said cap substantially closing the protecting casing and having an opening in its outer part to permit the insertion of the key, and a disk provided with a key slot rotatably mounted 60 in said opening.

4. The combination with a cylinder lock comprising a lock spindle, a key and suitable tumblers, and a casing surrounding said tumblers and spindle adapted to be mounted 65 in a door, of a protecting casing comprising a sleeve member surrounding the said casing adapted to be secured to the inner side of a door and extending into the door and a cap having its outer end at the outer side 70 of the door, extending inwardly therefrom and overlapping and secured to the sleeve member in the interior of the door, said cap substantially closing the protecting casing and having an opening in its outer part to 75 permit the insertion of the key, a disk provided with a key slot rotatably mounted in said opening, and a plate secured to the inside of said cap and confining a portion of said disk between itself and the outer part 80 of the cap.

5. The combination with a cylinder lock comprising a lock spindle, a key and suitable tumblers, and a casing surrounding said tumblers and spindle adapted to be mounted 85 in a door, of a protecting casing comprising a sleeve member surrounding the said casing adapted to be secured to the inner side of a door and extending into the door and a cap having its outer end at the outer side of the 90 door, extending inwardly therefrom and overlapping and secured to the sleeve member in the interior of the door, said cap substantially closing the protecting casing, the overlapping portions of the said members 95 having engaging threads and aligned openings, and a securing member passed through and secured in said openings and pressing against the said first named casing.

In testimony whereof I affix my signature. 100

LEOPOLD SCHONWALD.
